(57) **CLAIM**

The ornamental design for a motorcycle starter cover, as shown and described.

DESCRIPTION

FIG. 1 is a front perspective view of the motorcycle starter cover of the present invention.

FIG. 2 is a front elevation view thereof.

FIG. 3 is a rear elevation view thereof.

FIG. 4 is a top view thereof.

FIG. 5 is a bottom view thereof.

FIG. 6 is a right side view thereof; and,

FIG. 7 is a left side view thereof.

The rear surface, front surface portions and connectors of the motorcycle starter cover disclosed in broken lines are shown for illustrative purposes only and form no part of the claimed design.
